DESIGN FOR A COMBINED SCARF AND CAP

Max Stuchin, Brooklyn, N. Y.

Application March 31, 1938, Serial No. 76,202

Term of patent 3½ years

To all whom it may concern:

Be it known that I, Max Stuchin, a citizen of the United States and resident of Brooklyn, in the county of Kings, and State of New York, have invented a new, original, and ornamental Design for a Combined Scarf and Cap, of which the following is a specification, reference being had to the accompanying drawing, forming a part thereof.

Fig. 1 is a top plan view of a combined scarf and cap, showing my new design.

Fig. 2 is a front perspective view of the same.

Fig. 3 is a side perspective view of the same.

I claim:

The ornamental design for a combined scarf and cap, as shown.

MAX STUCHIN.
